UNITED STATES PATENT OFFICE.

FRANCIS G. DIETZ, OF NEW YORK, N. Y.

DESIGN FOR A GARMENT-SUPPORTER.

SPECIFICATION forming part of Design No. 35,613, dated January 28, 1902.

Application filed December 5, 1901. Serial No. 34,837. Term of patent 14 years.

To all whom it may concern:

Be it known that I, FRANCIS G. DIETZ, a citizen of the United States, residing at New York, in the county of New York and State of New York, have invented and produced a certain new and original Design for Garment-Supporters, of which the following is a specification.

My invention resides in the design for a garment-supporter shown in the accompanying drawings, in which—

Figure 1 is a perspective view of a garment-supporter made in accordance with my design. Fig. 2 is a top view of the same, and Fig. 3 is an edge view.

As illustrated, the garment-supporter made according to my design consists of a base 1 and a hook 2, connected therewith. The base 1 is made from a thin sheet of material bent at a point intermediate its ends to form the two sides 3 and 4, the side 3 constituting what may be termed the "back" and the side 4 the "front." Said sides are connected to each other along the line of the bend referred to by a substantially circular web 5. The back 3 projects at its side edge beyond

the corresponding edge of the front 4 and is provided with elongated openings 6. The front 4 has formed in its inner surface a longitudinally-extending groove 7, parallel to the side edge of said front and producing on the front face thereof a projection 8. The inner end of the hook 2 fits within the groove 7 and is secured thereto by rivets 9, whose inner ends extend beyond the plane of the inner surface of the front 4 to form projections 10. From the upper end of the front 4 the hook 2 extends upwardly and then downwardly in a plane at right angles to said front 4 to form a downwardly-facing loop 11.

Having now described my invention, what I claim is—

The design for a garment-supporter, substantially as shown and described.

In testimony whereof I have hereunto set my hand in presence of two subscribing witnesses.

FRANCIS G. DIETZ.
